UNITED STATES PATENT OFFICE.

ERNEST M. HICKS, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

CAPPED-HUB MINE-CAR WHEEL.

1,199,787.

Specification of Letters Patent.

Patented Oct. 3, 1916.

Application filed November 22, 1915. Serial No. 62,891.

To all whom it may concern:

Be it known that I, ERNEST M. HICKS, residing at Berwick, Pennsylvania, and being a citizen of the United States, have invented certain new and useful Improvements

5 in Capped-Hub Mine-Car Wheels, of which the following is a full, clear, and exact description, such as will enable others skilled in the art to which it appertains to make and to use the same, reference being had 10 to the accompanying drawings, which illustrate the preferred form of the invention, though it is to be understood that the invention is not limited to the exact details 15 of construction shown and described, as it is obvious that various modifications thereof will occur to persons skilled in the art.

In said drawings: Figure 1 is an elevational view of the improved wheel herein-after described. Fig. 2 is a vertical sectional view, the section being taken on line 2—2 of Fig. 1. Fig. 3 is an elevational view of the hub cap hereinafter described. Fig. 4 is a plan view of said hub cap. Fig. 5 is 20 an enlarged fragmentary detail view. Fig. 6 is a sectional view, the section being taken on line 6—6 of Fig. 1, showing how the hub cap is locked in position; and Fig. 7 is a sectional view taken on the same line with 25 the lug of the hub cap and the key employed to lock said hub in position, both removed.

The object of the invention is to provide a simple form of mine car wheel of the self-lubricating type which is composed of parts 30 which may be assembled where used and, when once assembled, will not require disassembling until it becomes necessary to remove the wheel from the axle upon which it is secured for service.

40 A feature of advantage is that but a small amount of machine work is necessary in the fabrication of the wheel and its associate parts and thereby the cost of manufacture is reduced to a minimum.

45 Another advantage is that the wheel may be used on either a straight axle, that is, an axle of uniform diameter from end to end, or on axles which have a portion of their ends of reduced diameter.

50 Other features of advantage will be apparent from the following description.

Referring particularly to the parts, 8 indicates generally the hub portion of the wheel which is provided with an oil chamber 55 9, adapted to contain oil or other suit-

able lubricant, which may find its way through orifices 10 to the axle 11, the lubricant being inserted through the lubricant valve 13 inserted in the face of the hub as now common in this type of wheel.

60

The hub portion of the wheel is provided with an inwardly extending sleeve 14, which is adapted to enter a journal box—not shown—which journal box is commonly employed in this type of construction and is 65 secured to one of the sills or to some other convenient part of the car. Extending outwardly from the face of the hub 8, are shouldered portions 15 which, as will be noted in Figs. 6 and 7, are each provided 70 with an enlarged opening 16 at one side and with a stop wall 17 at the opposite side, a passage 18 being provided through said wall 17 for the reception of a locking key hereinafter referred to. Any number of 75 parts 15 may be provided, though three have been found to be sufficient and three only are illustrated.

The hub cap 20 is provided with wedge shaped lugs 21 corresponding in number 80 and spacing to the parts 15 just referred to, said lugs being of such sectional area that they will readily pass into openings 16 and leave a space for the passage of the locking keys 22 as shown in Fig. 6 when the hub cap 85 has been partially rotated to insert the lugs 21 in the openings 16 in contact with the walls 17 before indicated. After the lugs have been thus positioned, keys 22 are inserted, driven home and the reduced end 90 portions 23 are upset as shown in Fig. 6, thereby securing the locking keys 22 in position and, due to the coincidence of the inclined faces 24 of the locking keys 22 and the inclined faces 25 of the lugs 21, the lugs 95 21 will be securely locked in position by said keys, thereby securing the hub cap 20 to the wheel hub 8.

As the lubricant has a tendency to find its way through the outer face of the hub, 100 it is preferred that a washer 30 be interposed between the hub 8 and the hub cap 20, which washer may be and preferably is a compressible material into which the perimetrical portion of the hub cap shall be 105 seated when the keys 22 are driven home as before indicated thereby preventing a loss of lubricant from the interior of the hub of the wheel.

In the form of construction shown a cap 110

washer 33 is slipped over the reduced end portion 11^a of the axle and said cap washer is secured in position by means of a cotter pin 35 projected through coincident orifices 5 in the barrel portion of the washer 33 and the reduced end of the axle 11^a.

What I claim is:

1. The combination in a wheel, of a fixed hub and rim portion provided with shouldered portions projecting longitudinally of the hub and a hub-cap adapted to rotatably interlock with said shouldered portions.
2. In a car wheel, a hollow hub portion with integral perforated lugs outstanding therefrom, a hub-cap adapted to interlock with said lugs upon partial rotation thereof and means interlocking with said hub-cap and lugs to lock said hub-cap in position.
3. In a car wheel, a hub portion and a hub-cap each being provided with outstanding portions adapted to interlock with coincident outstanding portions on the other upon partial rotation of said hub-cap and flexible locking means therefor.
4. The combination in a wheel, of a cast hub provided with shouldered portions extending beyond its outer face, a hub cap provided with lugs adapted to register with said shouldered portions, a compressible

washer interposed between the wheel hub 30 and said hub cap, and means adapted to force the hub cap into engagement with said washer.

5. The combination in a wheel, of a cast hub provided with shouldered portions extending beyond its outer face, a hub cap provided with lugs adapted to register with said shouldered portions, a compressible washer interposed between the wheel hub 35 and said hub cap, and means adapted to lock the hub cap in position and at the same time force the hub cap into engagement with said washer.

6. The combination in a mine car wheel, of a cast rim and a hub portion, the latter 45 being provided with outstanding shouldered portions, a hub cap having lugs thereon adapted to register with said shouldered portions, and locking keys adapted to engage the shouldered portions of the hub and 50 the lugs on the hub cap to secure the latter in position.

In witness whereof I have hereunto set my hand in the presence of two witnesses.

ERNEST M. HICKS.

Witnesses:

F. N. RITTER,
FRED A. HOFFMAN.
